Seth E. Clapp

United States Patent Office.

SETH E. CLAPP, OF CAMBRIDGE, MASSACHUSETTS, ASSIGNOR TO HIMSELF
AND JOHN J. RIDGWAY.

Letters Patent No. 77,583, dated May 5, 1868.

IMPROVED BISCUIT-CUTTER.

The Schedule referred to in these Letters Patent and making part of the same.

TO ALL WHOM IT MAY CONCERN:

Be it known that I, SETH E. CLAPP, of Cambridge, in the county of Middlesex, and State of Massachusetts, have invented certain new and useful Improvements in Biscuit-Cutters; and I do hereby declare the following to be a full and exact description thereof, reference being had to the accompanying drawings, and to the letters of reference marked thereon.

To enable others skilled in the art to make and use my invention, I will proceed to describe its nature, construction, and use.

The nature of my invention consists in making, as a new article of manufacture, a revolving hand-biscuit and confectionery-cutter.

Drawings.

Figure 2 is a cross-section of the same.

Figure 3 is a perspective of the inner cutter.

In the drawings, I have represented my invention as it appears when used for cutting jumbles, that is, round cakes having the centre cut out; but for many purposes I remove the centre-piece, (see fig. 3,) and use the other part for cutting biscuits, crackers, &c.

In fig. 1, A A' represent two handles, which are attached to the main cutter B B'. The cutter B B' assumes the form shown in the drawings, and is made as follows: First, a cylinder is made of the desired dimensions, that represented in fig. 2 for instance; then on the cylindrical part of its surface three circles are laid out, that is, they would be circles if the cylinder were developed. These circles are not quite tangent to each other, but leave a small space, which is represented in perspective by C C' C'', and in section in fig. 2. Now, if all that part of the cylinder within these circles is cut away, and the surplus material outside the circles be also cut away, we shall have an article in form as represented in fig. 1.

If this cutter be revolved on a sheet of dough, it will cut circular cakes.

The centre-piece, D D' D'', is made as shown, or in any desirable form, and is provided with two arms, H H', one end of which, H, has a tongue projecting from it, which is designed to fit a corresponding notch in K', fig. 1; the other end, H', is coned so as to fit into the conical seat in K, fig. 1.

To remove the centre-piece, we have simply to unscrew K by means of K'', fig. 1.

My improved cutter may be varied in size and shape, so as to adapt it for cutting various kinds of cake and confectionery.

Having thus described my invention, I will now proceed to set forth my

Claim.

What I claim as my invention, is—

As a new article of manufacture, the biscuit-cutter, either with or without the centre-piece D D' D'', substantially as described and for the purpose set forth.

SETH E. CLAPP.
